UNITED STATES PATENT OFFICE.

CHARLES C. NEWTON, OF PHILADELPHIA, PENNSYLVANIA, ASSIGNOR TO
NEWTON MACHINE TOOL WORKS, INCORPORATED, OF PHILADELPHIA,
PENNSYLVANIA, A CORPORATION OF PENNSYLVANIA.

DESIGN FOR A STANDARD FOR MACHINE-TOOLS.

SPECIFICATION forming part of Design No. 35,181, dated October 15, 1901.

Application filed September 13, 1901. Serial No. 75,355. Term of patent 14 years.

To all whom it may concern:

Be it known that I, CHARLES C. NEWTON, a citizen of the United States, residing in Philadelphia, Pennsylvania, have invented and produced a certain new and original Design for a Standard for Machine-Tools, of which the following is a specification.

My design for the standard of a milling-machine is clearly illustrated in the accompanying drawings, in which—

Figure 1 is a perspective view of the standard. Fig. 2 is a side view looking in the direction of the arrow 2, Fig. 4. Fig. 3 is a side view looking in the direction of the arrow 3, Fig. 4. Fig. 4 is a sectional plan view on the line 4 4, Fig. 2.

The essential feature of the design is the vertical ribs on two adjoining sides of the standard, as illustrated.

A is a base from which projects the stand-

ard B. This standard has two adjoining surfaces b b' and at right angles to each other, and at each side of the surface b are vertical ribs d d , separated by a channel d' , and on the surface b' are vertical ribs e e , separated by a channel e' . The other two sides b^2 b^3 are inclined, giving the peculiar effect shown in the drawings.

I claim—

The design for a standard for machine-tools, as herein described and as illustrated in the accompanying drawings.

In testimony whereof I have signed my name to this specification in the presence of two subscribing witnesses.

CHARLES C. NEWTON.
